(57) **CLAIM**

The ornamental design for an insulating container for beverage with straw, as shown and described.

DESCRIPTION

FIG. 1 is a right side view of an insulating container for beverage with straw showing my new design;

FIG. 2 is a front view thereof;

FIG. 3 is a rear view thereof;

FIG. 4 is a left side view thereof;

FIG. 5 is a top right perspective view thereof;

FIG. 6 is an exploded view thereof, shown in a reduced scale;

FIG. 7 is a bottom perspective view thereof;

FIG. 8 is a bottom plan view thereof; and,

FIG. 9 is a top plan view thereof.

All broken lines in the figures illustrate the portions of the insulating container for beverage with straw, and form no part of the claimed design.
